UNITED STATES PATENT OFFICE.

FRANK L. COES, OF WORCESTER, MASSACHUSETTS, ASSIGNOR TO LORING COES & COMPANY, INCORPORATED, OF WORCESTER, MASSACHUSETTS, A CORPORATION OF MASSACHUSETTS.

CONSTRUCTION OF WRENCH-HANDLES.

SPECIFICATION forming part of Letters Patent No. 693,108, dated February 11, 1902.

Application filed November 28, 1901. Serial No. 83,406. (No model.)

To all whom it may concern:

Be it known that I, FRANK L. COES, a citizen of the United States, residing at Worcester, in the county of Worcester and State of Massachusetts, have invented a new and useful Improvement in the Construction of Wrench-Handles, of which the following, together with the accompanying drawings, is a specification sufficiently full, clear, and exact

5 to enable persons skilled in the art to which this invention appertains to make and use the same.

My present invention relates to the manner of constructing and combining the metal handle-frame and non-metallic side plates, wherein I employ a series of inwardly-bent integral fingers formed on the edges of the handle-frame at intermediary positions and engaging with circumferentially-curved recesses in

10 the edges of the side plates, the object being to afford a neat, efficient, and desirable handle that can be manufactured with convenient facility.

To this end my invention consists in a wrench-handle structure such as shown in the accompanying drawings, wherein—

Figure 1 is a side view of a wrench having a handle embodying my improvements. Fig. 2 is a rear view of the handle. Fig. 3 is a separate edge view of one of the scales or side plates. Fig. 4 is a side view of the same. Fig. 5 shows a transverse section at line W X of the handle-frame. Fig. 6 is a transverse section at line X X. Fig. 7 is a section of the side plate at line Y Y, and Fig. 8 is a section of the side plate at line Z Z.

Referring to the drawings, A indicates the wrench-bar, having the reduced shank portion A' at one end and the fixed jaw a at the

40 other end.

B indicates the movable jaw, and C the adjusting-screw, having the thumb-boss or rosette thereon, which parts can be of well-known or suitable structure.

D indicates the handle-frame of malleable iron, comprising the collar portion 2 with the overhanging ferrule-rim 3, projecting screw-bearing step 4, and the integrally-attached longitudinal edge bars D', their inner edges

45 adapted for embracing the edges of the bar-

shank A' and their outer edges formed to the contour of the handle shape, the opposite edge bars being integrally united transversely across the shank-receiving space by a bridging or web D² at one or both sides thereof, as 55 heretofore employed.

In accordance with my invention the handle-frame is provided at its opposite edges with a plurality of projecting prongs or fingers 5, disposed at suitable intervals between 60 the rim 3 of the collar and the tip or end piece E, said fingers being formed or cast integral with the metal handle-frame and primarily project outward from the outer angles of the edge bars, as indicated in Fig. 5. 65 The projecting fingers are best made of a flat rectangular form in cross-section, with their ends of a semicircular or rounded shape, as shown.

F indicates the wood or non-metallic side plate, which has its outer side formed to the handle shape and its inner side formed to seat upon the handle-frame. At the exterior, upon the edges of the side plates F and at intervals corresponding with the fingers 5, I form partly-75 circumferential recesses 6 by means of a suitable rotating end cutter employed in such manner that the bottom of the recess will have a curvature approximating or somewhat similar to the transverse curvature of the exterior 80 surface of the handle or plate. (See section Figs. 6 and 7.) The recesses 6 commence at the edges of the plate and extend circumferentially to the points represented, or about one-fourth of the circle around the handle, 85 more or less, and terminate in semicircular form.

The dimension of the fingers 5 and recesses 6 in a direction longitudinally of the handle is about three-eighths of an inch, more or 90 less, and the thickness radially about one-eighth of an inch, more or less, the outer end of the finger being approximately the same circle as that of the rotary cutter by which the recesses are formed. The ends of the side 95 plate may have the usual tenons 8 and 9 to lock under the ferrule-rim 3 and end piece E.

When the parts of the wrench are assembled, the side plates are seated upon the sides of the handle-frame, and the fingers 5 are then 100

bent inward and closed down into the recesses 6 by means of suitable dies or machinery, causing the several fingers to clasp the edges of the handle-plate and take firm hold 5 on the inwardly-curved bottom surfaces of the recesses, as illustrated in section, Fig. 5. The exterior of the fingers 5 are finished flush and smooth with the exterior of the handle-plates F.

10. What I claim as of my invention, and desire to secure by Letters Patent, is—

1. A wrench-handle comprising a metal central frame with wooden side plates seated thereon; said frame being provided at its 15 edges with projecting integrally-formed inwardly-bent fingers that engage in circumferential recesses formed on the opposite edges of said side plates, substantially as set forth.

2. The handle-frame provided at each of its 20 edges with a plurality of projecting fingers disposed at intervals between the collar-rim and end piece, in combination with side plates

having circumferentially-disposed recesses into which said fingers are clasped with inward curvature.

3. In a wrench, the combination, of a handle-frame comprising a collar portion with screw-bearing step and ferrule-rim, longitudinal edge bars united by a web bridging the bar-space, and provided with a series of projecting inwardly-bent curved fingers at the opposite edges all integrally formed or cast in a single piece, the wrench-bar having a shank fitting within said frame, and the non-metallic side plates seated on said frame and 30 having at their edges curved recessed surfaces embraced by the inwardly-bent ends of said fingers.

Witness my hand this 21st day of November, 1901.

FRANK L. COES.
